INVENTOR,

William C. Heister,
By A. S. Coulmin
Attorney.

UNITED STATES PATENT OFFICE.

WILLIAM C. HEISTER, OF SPRINGFIELD, OHIO.

HYDROCARBON-OIL BURNER.

SPECIFICATION forming part of Letters Patent No. 392,802, dated November 13, 1888.

Application filed March 1, 1888. Serial No. 265,863. (No model.)

To all whom it may concern:

Be it known that I, WILLIAM C. HEISTER, a citizen of the United States, residing at Springfield, in the county of Clark and State 5 of Ohio, have invented certain new and useful Improvements in Hydrocarbon-Oil Burners, of which the following is a specification, reference being had therein to the accompanying drawings.

10 This invention relates to certain new and useful improvements in hydrocarbon-oil burners, and is specially intended to be used in connection with heating-stoves, domestic furnaces, and boiler-furnaces.

15 The invention consists, essentially, of a burner having a series of radial chambers, a number of air-passages leading thereto at or near the inner end, of a common oil-chamber into which the oil is primarily introduced, and 20 of a series of burner-tubes leading from said chamber into and partially through said radial chambers, whereby oil and air are brought together within said chambers for the purpose of burning the same in a combined 25 or commingled state, to intensify the resulting heat and economize in the consumption of the hydrocarbon liquid.

The invention also consists in constructing the outer ends of the oil-conduits with reduced 30 passages which lead into the radial chambers for the purpose of reducing the oil to a fine stream, which shatters and commingles with the air in the chamber in a broken or finely-communited condition, effecting a more perfect union of the two elements.

The invention also consists of certain other details of construction and arrangement hereinafter more fully appearing.

40 In the accompanying drawings, forming a part of this specification, and on which like reference-letters indicate corresponding parts, Figure 1 represents a sectional view of the lower portion of a heating-stove of any approved construction and a partial elevation and partial sectional view of my improved oil-burner; Fig. 2, a detail perspective view of the burner proper; Fig. 3, an inverted plan view of the central part of the burner with a 45 portion broken away to show the interior construction; Fig. 4, a plan view of a portion of the base-plate, showing the arrangement of the air-passages thereof; and Fig. 5, a detail sectional view of a modified form of oil-pipe.

The letter A designates the lower portion of 55 a heating-stove of any of the approved types with which I contemplate using my invention. It should be observed, however, that it is equally applicable to domestic heating-furnaces and to the various kinds of boiler-furnaces, both stationary and portable.

The letter B designates the usual grate-bars, upon which I place and suitably secure the base-plate C, which consists of an annular flat casting with a series of air-passages, D, being, 60 65 preferably, one passage for every radial chamber of the burner.

An annular slide, E, is placed upon the base-plate and guided between suitable lugs, F. This plate has a corresponding series of air-passages, and is manipulated by engaging a pin, G, or other suitable device with a poker or other instrument, for the purpose of regulating the size of the air-passages D, so as to determine the supply of air which is afforded 70 to the outer ends of the radial chambers and which intensifies combustion. The base-plate is further provided with a number of inner air-passages, H, and with a hub, I, through which passes an oil-supply tube, J. This tube 75 80 is connected with a suitable supply-pipe, K, which leads to an oil tank or reservoir located at a suitable elevation to cause the oil to flow freely out of the upper end of the tube J. This end of the tube is provided with a contracted opening formed in a bushing, L, of lava or other earthenware. The reduced orifice supplies the oil to a chamber (hereinafter described) in a gradual and uniform manner.

An annular flange, M, of the plate C encircles 90 the hub I and forms between its inner wall and the outside of the hub a tapering seat, into which the burner proper is seated. This burner consists of a body, O O', through which project any suitable number—six in the present instance—95 of radial chambers P, preferably cast in the body. Cast-iron is the preferred material. The lower end of the body is tapered, as seen at Q, to fit the above-described seat, whereby a cheap and tight joint is formed. An eye, R, 100 may be formed on the upper part of the body to afford a ready means of removing and replacing it from and to its seat while in a stove or furnace. A series of vertical air-passages, S, are formed in the body and lead into the 105 chambers P and communicate with the air-passages H, which open toward the lower part of the stove or furnace and are arranged to re-

ceive upward drafts of air. The central portion of the body O is formed with a chamber, T, which fits over the hub I and into which the tube J discharges oil. From this oil-chamber 5 burner-tubes U project across the air-passages S and into the chamber P. These burner-tubes are preferably of metal and provided at their outer ends with bushings V, of lava, fire-clay, or other earthen substance, in which a suitable 10 orifice is formed to cause the oil to flow from the burner-tubes in the form of small jets, which spray and shatter into the outer portion of the inclosing-chambers P. The heat is intense at the outer ends of the burner-tubes, and it is 15 to prevent their destruction (when of metal) by oxidation or corrosion that I provide them with the bushings V, which I have ascertained by practice are not affected by the intense heat.

20 In Fig. 5 I have illustrated a modified form of burner-tube, which consists of making it entirely of the substance above alluded to and without employing any metal whatever.

The pressure of the oil from the source of 25 supply more or less fills the chamber T, whence the oil flows into the burner-tubes and spouts from the bushing V in the form above spoken of. As soon as ignited at the outer ends of the 30 chambers P a draft is created up through the passages H and S and out through the chambers P. When the air passes the outer ends of the burner-tubes, it commingles with the sprays of oil, and the two elements in a commingled 35 condition are burned, the heat decomposing the air into its constituent gases. Thus an intense heat is secured and economy effected in the consumption of the oil. The air thus introduced to the chambers P gradually becomes more highly heated as it passes into the passages H 40 and S and to the chambers P, rendering it in better condition to take up the sprays of oil. To intensify the draft, and therefore the heat, the slide E is manipulated to open the draft-passages D. The air drawn up through these 45 passages grows hotter as it nears the chambers P, which stand above them. As the flames occupy the outer ends of these chambers and issue upward from their termination, the heat is intense at these points and the upcoming 50 air is quickly taken up and decomposed.

The device here shown and described I have subjected to actual usage, and find that with a burner measuring about seven inches from point to point diametrically and otherwise of 55 about the size shown I have filled with flames the entire interior of a stove with a fire-space of about twenty inches diameter and four feet high. A suitable cut-off is interposed in the pipe K to control the amount of oil which 60 passes to the chamber T. Whatever space there may be between the base-plate and the inner wall of the stove or furnace I close by filling of clay or other suitable substance. The body O' of the burner proper acts to 65 somewhat deflect the air rising up through the passages D outward, whence it freely es-

capes upward and commingles with the flames. This is the preferred manner of constructing the burner proper, though it may be otherwise constructed.

Having thus fully described my invention, what I claim as new, and desire to secure by Letters Patent, is—

1. In a burner, the combination, with a base-plate having outer draft-passages, a regulating-slide therefor, inner draft-passages, a central oil-supply tube, and an annular seat above the said inner passages, of a burner proper consisting of a body fitted within the said seat, and having air-passages extending 70 upwardly from said inner passages of the plate, radial chambers extending from said vertical passages, a central oil-chamber communicating with the supply-tube, and burner-tubes extending from said chamber across 75 the vertical air-passages and partly through the radial chambers.

2. In a burner, a base-plate having a central hub and a series of inner air-passages 80 around said hub, a series of outer air-passages and a regulating slide, and a seat formed for the reception of a burner at the outer ends of said inner air-passages.

3. In a burner, the combination, with a base-plate having a central opening therein 85 and an oil-tube fitted to said opening and provided with a bushing of earthy substance at its discharge end, of a burner proper fitted upon the said base-plate and having an air-chamber which incloses the said oil-tube 90 at the end in which the bushing is fitted.

4. In a burner, the combination, with a burner proper consisting of a body having one end fashioned to enter a seat and having an interior chamber and burner-tubes extending from said chamber, air-passages 105 which lead around and to said burner-tubes, and radial chambers which envelop the burner-tubes and extend beyond them and open at their inner ends into the said air-passages, of a base-plate having a central oil-supply tube discharging into the said burner-chamber, air-passages about the said tubes which communicate with the air-passages of the burner, a seat in which the burner is fitted, 110 and a pipe leading to said oil-tube.

5. A burner proper consisting of a body, O, having air-passages S, a central oil-chamber, around which said air-passages are disposed, radial chambers P, communicating 120 with said passages, respectively, and burner-tubes U, communicating with said oil-chamber, and extending through and across said passages S into and partly through said radial chambers.

In testimony whereof I affix my signature in presence of two witnesses.

WM. C. HEISTER.
